DESIGN FOR A HOSIERY DISPENSING MACHINE

Robert Charles Hopkins, Rockville Centre, N. Y.

Application April 7, 1938, Serial No. 76,341

Term of patent 3½ years

To all whom it may concern:

Be it known that I, Robert Charles Hopkins, a citizen of the United States and a resident of Rockville Centre, in the county of Nassau, Long Island, and State of New York, have invented a new, original, and ornamental Design for a Hosiery Dispensing Machine, of which the following is a specification, reference being had to the accompanying drawing, forming a part thereof.

Figure 1 is a front elevation of the hosiery dispensing machine showing my new design, and
Figure 2 is a side view of the same.

I claim:

The ornamental design for a hosiery dispensing machine, as shown.

ROBERT CHARLES HOPKINS.
